CLAIM

The ornamental design for a gaming machine deck, as
shown and described herein.

DESCRIPTION

FIG. 1 is a first top front perspective view of a gaming
machine deck of one embodiment of our new design.

FIG. 2 is a second top front perspective view of the gaming
machine deck of FIG. 1.

FIG. 3 is a top view of the gaming machine deck of FIG. 1.
FIG. 4 is a bottom view of the gaming machine deck of FIG.
1.

FIG. 5 is a right side view of the gaming machine deck of
FIG. 1.
FIG. 6 is a left side view of the gaming machine deck of FIG.
1.

FIG. 7 is a front view of the gaming machine deck of FIG.
1.

FIG. 8 is a rear view of the gaming machine deck of FIG. 1.
FIG. 9 is a first top front perspective view of a gaming
machine deck of another embodiment our new design.

FIG. 10 is a second top front perspective view of the gaming
machine deck of FIG. 9.

FIG. 11 is a top view of the gaming machine deck of FIG.
1.

FIG. 12 is a bottom view of the gaming machine deck of
FIG. 1.

FIG. 13 is a right side view of the gaming machine deck of
FIG. 1.

FIG. 14 is a left side view of the gaming machine deck of
FIG. 1.

FIG. 15 is a front view of the gaming machine deck of FIG.
1; and,

FIG. 16 is a rear view of the gaming machine deck of FIG.
1.

In the drawings, the evenly-spaced broken lines depict
environment and form no part of the claim; the dash-dot-
dash lines represent boundaries of the claimed design and
form no part thereof.
